UNITED STATES PATENT OFFICE

GEORGE L. N. MEYER, OF JACKSON HEIGHTS, NEW YORK, ASSIGNOR TO GEO. J. MEYER
MANUFACTURING COMPANY, OF CUDAHY, WISCONSIN, A CORPORATION OF WIS-
CONSIN

WASHER FOR BOTTLES OF DIFFERENT SIZES

Application filed December 12, 1928. Serial No. 325,449.

This invention has for its object to provide a bottle washing machine capable of operating simultaneously upon bottles of different sizes.

5 Another object of the invention is to provide attachments for a bottle washing machine adapting it for this purpose.

With the above and other objects in view the invention consists in the bottle washer 10 for bottles of different sizes as herein claimed and all equivalents.

Referring to the accompanying drawings, in which like characters of reference indicate the same parts in different views,

15 Fig. 1 is a side view of a portion of a bottle washing machine embodying the features of the present invention;

Fig. 2 is a transverse sectional view thereof through one of the rows of brushing spindles 20 and showing the bottles of different sizes clamped and undergoing the brushing operation;

Fig. 3 is a similar view showing the brushes withdrawn and the bottles unclamped;

25 Fig. 4 is a view similar to Fig. 1 showing two rows of bottles clamped and ready for the brushing operation, parts being sectioned on the left of said figure through the end bottle station and on the right of said figure 30 through the next bottle station, and

Fig. 5 is a view similar to Fig. 3, of a modified form of brush tube extension.

In these drawings, 10 indicates the frame of the machine or so much thereof as is necessary to illustrate the inside brushing mechanism of the bottle washing machine, which is of the type covered by Letters Patent 1,429,960 to George J. Meyer, dated September 26, 1922. On this frame is mounted a 35 traveling endless chain conveyer made up of articulated rows of pockets 11 carrying bottles and supported by rollers 13 traveling on angle tracks 14. The intermittently moving chain conveyer serves to bring the bottles in 40 an inverted position to the inside brushing mechanism, with which the present invention is concerned, and to conduct them therefrom, as well as similarly serving other mechanism, not shown. The portion of the stationary 45 frame 10 shown forms a vertical guideway 50

15, within which three distinct mechanisms operate to clamp the bottles above and below and to insert rotating fountain cleaning brushes therein while so clamped. The upper clamping mechanism 16 has slide bearing 55 projections 17 traveling in the slots 15, and is connected at both ends by adjustable extensible connecting rods 18 with walking beams or levers 19 fulcrumed at 20 on the frame, the other ends of said levers having adjustable 60 link connections 21 with the lower clamping members 22, and link connections 23 with suitably actuated operating levers 24. Thus, when the operating levers 24 are raised from the position shown in Fig. 1, they swing the 65 walking beams 19 to lift the lower clamping members 22 and lower the upper clamping members 16 to clamp the bottles between them in a manner which will later appear.

The hand wheel 25 on walking beam levers 70 19 is for simultaneously adjusting the length of both of the extensible link members 18 to vary the distance between the upper and lower clamping members and thereby adapt the machine for bottles of different sizes. 75 This adjustment, however, is to take care of changes in the sizes of the bottles operated upon throughout the whole row of bottles in each bottle carrier, that is it affords adjustment for changing the entire machine from 80 pint size bottles to quart size bottles, for example.

The lower clamping mechanism 22 is likewise mounted on slide bearing projections 26 traveling in the vertical guideways 15. Also 85 27 the brush mechanism or gear box thereon is slidably mounted on slide bearing projections 28 traveling in the vertical guideways 15 and is raised and lowered by suitable lever and link mechanism 29, only parts of which are shown, 90 and is provided with a gear shaft 30 having a pulley 31, which is driven in a suitable manner notwithstanding the traveling movements of the brushing mechanism.

When the clamping members 16 and 22 approach each other the bottles in the two rows of pockets in the position for inside brushing are clamped between spring-pressed funnel members 32 on the lower clamping member 95 engaging the mouths of the bottles and lift- 100

- ing the bottles slightly from their bearings in the pockets and top gauges 33 carried by the upper clamping member and engaging the upturned bottoms of the bottles. It is sufficient for the purpose of this invention to state that the top gauges 33 are carried by the upper clamping member 16, but in fact they are carried by swinging arms 34 pivotally mounted in rows across the upper clamping member held in their operative positions by pairs of spring-engaging fingers 35 thereon grasping diagonally opposite corners of square clamping rods 36, permitting the top gauges 33 to yield upwardly when subjected to an abnormal pressure and thereby lift a cross-bar 37 to operate a stop mechanism for stopping the operation of the machine in the manner covered in Patent 1,503,512 to George J. Meyer, dated August 5, 1924.
- 20 The bottle brushing mechanism includes a pair of rows of tubular brush spindles 38 carried on the gear box 27 and suitably driven by the shaft 30 thereof and supplied with water or other cleaning fluid under pressure 25 timed with the cleaning operation, such spindles carrying on their upper ends rotary cleaning brushes 39 extending well up against the bottoms of the bottles in the uppermost position of the brushing mechanism shown in 30 Fig. 2 and withdrawn into the central brush tube 40 in the lower position of the brushing mechanism, as shown in Fig. 3.

When the brushes are withdrawn within the brush tubes 40 and the lower clamping mechanism 22 is moved downwardly to release the bottles each spring-pressed funnel 32 with its brush tube moves upwardly until a stop 41 threaded on the end of the brush tube engages the bottom of the spring housing.

40 While it has heretofore been possible to change the entire machine from its adjustments for operating upon one size bottle to adjustments for operating on another size bottle, as previously mentioned, no provision 45 has been made for adapting the machine to operate on different size bottles at the same time and this is very desirable for, in the cleaning of bottles for some purposes, it is 50 more convenient to provide for one or more stations for smaller bottles in each row and so avoid the loss of time in changing adjustments. In the machine illustrated the end station in the bottle row is given over to the 55 use of small bottles 42, while all other stations in the row are given to the use of large bottles 43 and the machine is set or adjusted for operation on the large bottles. The difference in the length of the bottles is compensated for by providing a spacing block 44 between the top gauge 33 of the small bottle station and the swinging arm 34. Thus the smaller bottle may be clamped with the same degree of pressure with such clamping 60 movement of the clamping members as is

necessary to clamp the larger bottles and the safety stop feature is retained for the small bottles as well as the large bottles. This safety stop feature consists in the ability of the swinging arm 34 to be raised to stop the machine in the event of abnormal pressure being applied thereto, as when the brush is prevented from entering a bottle by the presence of a crown cap thereon. In that event the brush presses the bottle against the top gauge to lift the swinging arm 34 and cause the machine to be stopped as heretofore. It is also necessary to substitute a shorter brush spindle at the small bottle station provided with a smaller brush suitable for the smaller bottles and, as this brush spindle is subject to the same retracting movement as the longer spindles, there is a possibility that the brush may be carried so far beneath the brush tube 40 that it may be injured or fail to enter the brush tube on the next operation. To prevent this possibility the present invention provides an extension for the brush tube 40 which may consist of a flaring skirt 45, shown in Figs. 2 and 3, or a tubular extension 46 of the same diameter as the brush tube, as shown in Fig. 5. These extensions for the brush tube are preferably carried by a stop 41' so that, in order to adapt a bottle station for smaller bottles, a skirted or sleeved stop 41' is substituted for the ordinary stop 41. With this substitution a travel of the shorter brush spindle which would carry its brush beneath the brush tube will not injure the brush as the extension serves to keep the brush bristles directed upwardly, ready to reenter the tube and bottle and thus prevent the rapid wear of the brush which would result if the bristles were bent downwardly each time the brush was raised. Also 105 failure of the brush to reenter the tube is made impossible by the extension of the tube with either the flaring skirt 45 or the tubular extension 46 of the same diameter as the brush tube. The flaring skirt extension 45 is 110 desirable where the upper end of the brush spindle bearing 47 is to be accommodated therein, as shown in Fig. 2.

By means of the features of the present invention a bottle washing machine may have 115 one or more of its bottle stations readily adapted for bottles of smaller size by merely inserting the spacing block 44 between the top gauge and its swinging arm for that station using longer attaching screws 33' as 120 shown and by substituting the smaller brush and brush spindle and the tube extension so that, without change in the adjustment of the machine for operating on the larger bottles, the machine may be run with bottles of 125 both sizes.

The term "station" is used to indicate the bottle position in the row. Thus the end bottle, as shown in Fig. 2, of smaller size occupies one station, while the larger bottles oc- 130

cupy other stations and when the machine is set as shown the smaller size bottles will always be fed to that pocket or station of each carrier for which the station change has been made adapting it for such smaller bottles.

(5) What I claim as new and desire to secure by Letters Patent is:

1. In a bottle washing machine of the type in which rows of bottles in a series of stations are clamped between upper and lower clamping members and in which brush spindles carrying brushes are admitted to the bottles through brush tubes of the lower clamping members, means for adapting a bottle station to clean smaller bottles comprising an extension secured to the upper clamping member, a shorter brush spindle and smaller brush for said station, and an extension for the brush tube at said station secured to the lower 20 end of the tube to prevent the brush bristles bending backwardly.

2. In a bottle washing machine of the type in which rows of bottles in a series of stations are clamped between upper and lower clamping members and in which brush spindles carrying brushes are admitted to the bottles through brush tubes of the lower clamping members which tubes form parts of spring-pressed funnels for engaging the mouths of 30 bottles and which carry removable stops for limiting their upward movement, means for adapting a bottle station to clean smaller bottles comprising an extension secured to the upper clamping member, a shorter brush 35 spindle and smaller brush for said station, and an extension for the brush tube at said station carried by the stop at the lower end thereof to prevent the brush bristles bending backwardly.

40 3. In a bottle washing machine of the type in which rows of bottles are clamped between upper and lower clamping members and in which brushing members comprising spindles carrying brushes are admitted to the bottles 45 through brush tubes of the lower clamping members, means for accommodating a smaller bottle in one position in the row comprising a block forming a spacer between the upper clamping member and its support, a shorter 50 brushing member at said position in the row, and a sleeve forming an extension at the lower end of the brush tube to prevent the brush bristles bending backwardly.

55 In testimony whereof, I affix my signature.
GEORGE L. N. MEYER.
